UNITED STATES PATENT OFFICE.

WILLIAM G. HOUSKEEPER, OF PHILADELPHIA, PENNSYLVANIA, ASSIGNOR TO
WESTINGHOUSE LAMP COMPANY, A CORPORATION OF PENNSYLVANIA.

ELECTRICAL TERMINAL DEVICE.

1,099,091.

Specification of Letters Patent.

Patented June 2, 1914.

Application filed November 3, 1909. Serial No. 526,064.

To all whom it may concern:

Be it known that I, WILLIAM G. Hous-
keeper, a citizen of the United States, and
a resident of Philadelphia, in the county of
5 Philadelphia and State of Pennsylvania,
have invented a new and useful Improve-
ment in Electrical Terminal Devices, of
which the following is a specification.

My invention relates to electrical terminal
10 devices and particularly to such devices as
are adapted to engage and to conduct cur-
rent to or from a continuously moving con-
ductor, such as an incandescent lamp fila-
ment which is in course of preparation.

15 The object of my invention is to provide
a terminal device which will be unusually
effective for the purpose indicated, and
which will require but a minimum degree
of preparation and attendance when in use.

20 Figure 1 of the accompanying drawing
is a side view of a device constructed in ac-
cordance with the present invention. Fig.
2, is a vertical sectional view of the device
of Fig. 1, and Fig. 3 is a perspective view
25 of one of the parts of the terminal device.

The device comprises a cylindrical block
1 having a central aperture 2, the upper
end of which is cone shaped or counter-
sunk, an annular recess 3 surrounding the
30 central aperture 2, an aperture 4 larger than
the central aperture 2 at the bottom of the
annular recess 3, and a cross passage 5 con-
necting the annular recess 3 with the central
aperture 2. The block 1 is preferably amal-
35 gamated, and to that end is composed of
copper or other material with which mer-
cury may be readily amalgamated, or for
which it possesses a high degree of capillary
attraction, and which does not readily dis-
40 solve in mercury or render it impure, and
the annular recess, the apertures, and the
cross passage are filled, or partially filled,
with mercury, substantially as shown. As
the block is amalgamated, the mercury will
45 be held by surface tension in the apertures
and passages above mentioned. The con-
ductor 6, with which the device is adapted
to make electrical contact, passes through
the central aperture 2 and the mercury con-
50 tained therein.

For the best operation of the device, it
has been found advantageous to have the
upper and lower surfaces of the body of
mercury through which the conductor passes
55 of concave form, which forms are auto-

matically obtained, in the present instance,
by reason of the difference in diameters of
the apertures 2 and 4. The pressures per
unit of area that oppose and tend to over-
come the surface tension of the mercury 60
that spans the apertures 2 and 4 are the
same, but the area of the aperture 4 being
greater than that of aperture 2, a greater
pressure will be exerted in opposition to
the surface tension of the mercury across 65
the aperture 4 than is exerted in opposition
to the surface tension across the aperture
2. The result is that when the mercury
rises in the annular recess 3 and in the ap-
erture 2 above a certain height, the pres- 70
sure exerted thereby is more than sufficient
to overcome the surface tension of the mer-
cury across the aperture 4, and the mercury
will exude therefrom until the pressure is
reduced to such a degree that the surface 75
tension of the mercury may again sustain
its weight. The surface of the mercury
across the aperture 4 will therefore be con-
vex when the block contains the maximum
amount of mercury which the surface ten- 80
sion will sustain, while both the upper and
lower surfaces of the mercury in the ap-
erture 2 will be concave in form. Thus the
surfaces of the mercury in the aperture 2
will be caused to automatically assume the 85
most advantageous forms by simply filling
the annular recess 3 with mercury until it
begins to exude from the aperture 4. The
recess 3 also serves as a reservoir for mer-
cury and continually supplies the same to 90
the aperture 2 and maintains the recess 2
filled, thereby compensating for any losses
which may occur during the use of the de-
vice and keeping the surfaces of the mer-
cury of the proper form. 95

In the use of the device, the amount of
heat generated may be very high or exces-
sive, and, in order to convey the same away
and maintain the terminal at a reasonably
low temperature, the block 1 is embedded in 100
the lower part of another block 8, having a
central aperture 9 corresponding to and
communicating with the aperture 2, and an-
other aperture 10 that connects the annular
recess 3 and provides a passage for admit- 105
ting mercury to the said annular recess. The
outer circumferential face of the block 8 is
provided with a helical groove in which is
sealed a coil of tubing 11 through which
water flows for cooling the terminal. 110

It will, of course, be understood that the structural details of the device may be modified considerably without departing from the spirit or scope of the invention, and that, 5 if desired, the device may be employed for the purpose of conducting current to and from other conductors than incandescent lamp filaments.

I claim as my invention:

- 10 1. In an electrical terminal device, the combination with a block provided with two apertures differing in diameter, and a cross passage connecting the apertures, of mercury contained within the apertures and cross path.
- 15 2. In an electrical terminal device, the combination with an amalgamated body having two apertures differing in diameter and a cross passage connecting the apertures, of mercury contained within the apertures and cross passage.
- 20 3. In an electrical terminal device, the combination with a block having a central aperture, an annular recess surrounding the same, an aperture larger than the said central aperture at the bottom of the recess, and a cross passage connecting the annular recess to the central aperture, of mercury contained within the said apertures, recesses 25 and passage.
- 25 4. In an electrical terminal device, the combination with a block having a central aperture, an annular recess surrounding the same, an aperture larger than the said central aperture at the bottom of the recess, and a cross passage connecting the annular recess to the central aperture, of mercury contained within the said apertures, recess and passage, and another block engaging 30 the aforesaid block and provided with apertures communicating with the central aperture and recesses therein.
- 35 5. In an electrical terminal device, the combination with a block having a central aperture, an annular recess surrounding the same, an aperture larger than the said central aperture at the bottom of the recess, and a cross passage connecting the annular recess to the central aperture, of mercury contained within said apertures, recess and passage, and another block engaging 40 the aforesaid block and provided with apertures communicating with the central aperture and recesses therein.
- 45 50 5. In an electrical terminal device, the combination with a block having a central aperture, an annular recess surrounding the same, an aperture larger than the said central aperture at the bottom of the recess, and a cross passage connecting the annular recess to the central aperture, of mercury contained within said apertures, recess and passage, and another block engaging the afore-
- 55 said block and provided with apertures connecting with the central aperture and recess therein, and cooling coils engaging the latter block.
6. In an electrical terminal device, the combination with a body provided with apertures differing in diameter, a cross passage connecting the apertures, and a reservoir communicating with the apertures 60 and passage, of mercury contained within the apertures, cross passage and reservoir.
7. A device of the character described comprising an apertured body having a reservoir communicating with the aperture, 65 and mercury contained within the reservoir and suspended across the aperture by capillary attraction of the aperture walls.
8. A device of the character described comprising an apertured body having a reservoir communicating with the aperture, and a fluid conductor contained within the reservoir and suspended across the aperture by capillary attraction of the aperture walls.
9. A device of the character described 75 comprising an apertured body having a reservoir communicating with the aperture, and a fluid conductor contained within the reservoir and suspended across the aperture, the walls of the aperture having a positive 80 degree of capillary attraction for the fluid conductor.
10. A device of the character described comprising an apertured body having a reservoir communicating with the aperture, 85 and mercury contained within the reservoir and suspended across the aperture, the walls of the said aperture being amalgamated.
11. A device of the character described comprising a member having separated 90 parts and a reservoir communicating with the space between the said parts, and a liquid conductor contained within the reservoir and suspended between the said parts by capillary attraction.

In testimony whereof, I have hereunto subscribed my name this thirteenth day of October, 1909.

WILLIAM G. HOUSKEEPER.
